STORAGE AND VAPORIZING APPARATUS
FOR LIQUEFIED PETROLEUM GAS MIX-
TURES

John W. Du Rant, Kingstree, S. C.

Application March 12, 1951, Serial No. 215,148

6 Claims. (Cl. 62—1)

1

This invention relates to new and useful improvements in storage and vaporizing apparatus for liquefied petroleum gases, and more particularly pertains to apparatus of this character especially well adapted for vaporizing constant B. t. u. mixtures from liquefied petroleum gas mixtures.

The primary object of the present invention is to provide storage and vaporizing means for mixtures of liquefied petroleum gases, which will produce fuel vapors of substantially constant B. t. u. heating value, and in which the tendencies of such liquefied fuel mixtures to stratify will be effectively counteracted.

Still another important object of the present invention is to provide apparatus of this character which will operate with substantially undiminished efficiency throughout a wide range of fuel vapor demand.

A paramount feature in the present invention resides in the provision of spray means for spraying liquid from the bottom of one tank into the vapor space of the other tank during high demand periods, for effective vaporization therein and also for moving liquid from the bottom of said one tank onto the upper surface of the liquid in the other tank.

Another meritorious feature of the present invention resides in the construction and arrangement of the conduits and the check valves therein so that such conduits serve to move liquid from the bottom of either one of the tanks into the upper portion of the other tank upon the occurrence of appropriate pressure differentials between the tanks.

These, together with various ancillary features and objects of the invention which will later become apparent as the following description proceeds, are attained by the present invention, a preferred embodiment of which has been illustrated by way of example only in the accompanying drawings, wherein:

Figure 1 is a vertical longitudinal sectional view of the present invention, wherein the flow of fluids in the apparatus during the removal of fuel vapor therefrom is indicated by flow arrows;

Figure 2 is a sectional view similar to that shown in Figure 1, however, the flow arrows in this view indicate the direction of flow of fluids during the filling of the apparatus with liquefied gases;

Figure 3 is a vertical sectional view taken upon the plane of the section 3—3 of Figure 1, certain hidden details being indicated in dotted outline;

Figure 4 is an enlarged sectional detail view illustrating particularly the manner in which the

2

partition is secured in the main tank and the arrangement of the conduits with respect thereto, as well as the internal construction of the valves; and,

5 Figure 5 is another enlarged sectional detail view, this view illustrating particularly the construction of the spray section of one of the conduits; and,

10 Figure 6 is a sectional detail view taken upon the plane of the broken section line 6—6 of Figure 5.

Reference is now made more specifically to the accompanying drawings, wherein like numerals designate similar parts throughout the various

15 views, and in which the reference numeral 10 designates the subject matter of this invention generally. The apparatus 10 comprises a main tank 12 including a central cylindrical portion 14, the open ends of which are suitably closed by spherical shell segments 16. The tank 12 is preferably of welded steel construction throughout and it will be understood that the same will be of sufficient structural strength to safely contain the vapor pressures of the volatile materials to be

20 placed therein, with an adequate safety factor being added for the expected temperatures to which the tank 12 will be exposed. As is customary in an apparatus of this character, the tank 12 is preferably buried within the ground so that the same will be subjected to substantially constant temperatures throughout the year, or at least so that the same will not be subject to wide variations in temperature.

The interior of the tank 12 is divided into compartments 18 and 20 by a vertical partition 22, so that the tank 12 may be considered as actually being composed of two separate tanks defining the chambers 18 and 20. Like the tank 12, the partition 22 is preferably steel, and is provided with an integral peripheral flange 24 that is welded to the tank 12 as at 26.

While the partition 22 has been shown as positioned so that the chamber 20 is much larger than the chamber 18, it is contemplated that the partition 22 may be positioned in the tank

45 12 to give whatever relative proportions desired to the chambers 18 and 20. Moreover, if deemed expedient, entirely separate tanks, not shown, may be provided to furnish chambers 18 and 20.

50 An L-shaped conduit is provided which includes a horizontal portion 28 that extends through the partition 22 adjacent the top of tank 12 and a vertical portion 30 disposed in the chamber 18 that has its lower end disposed only a short distance above the bottom of the cham-

ber 18. In a similar manner, a similar L-shaped conduit is provided, the horizontal portion 32 of which extends through the partition 22 and the lower end of the vertical portion 34 of which is disposed adjacent the bottom of the chamber 20.

The horizontal portions 28 and 32 of the conduits extend through suitable apertures in the partition 22, and are sealed therethrough, as by welding 36 so that the only fluid communication between the chambers 18 and 20 is through the conduits.

Means is provided so that the only flow permitted in either of the conduits is such that fluids will pass upwardly in the vertical portions thereof. In the preferred form of the invention, such means comprises ball check valves 36 and 38 disposed in the horizontal portions 30 and 34 of the respective conduits. As will be readily understood upon reference to Figure 4 of the drawings, balls 40 in the valves 36 and 38 will unseat to permit upward flow in the conduits, but will gravitate to valve closing positions to prevent downward flow in the conduits.

As best shown in Figures 5 and 6, the horizontal portion 28 projects horizontally in the upper portion of the chamber 20 and such extension constitutes a spray section 42 of the conduit, inasmuch as such portion is provided with a plurality of discharge orifices 44. The orifices 44 are preferably arranged in parallel rows in the bottom of the spray section 42 arranged approximately twenty-five degrees from the vertical medial plane of the spray section 42 as clearly shown in Figure 6. The free end of the spray section 42 is closed and provided with a further orifice 46 arranged to project fluid downwardly and outwardly from the free end of the spray section 42. The spray section 42 is shown in a simple form, and it is within the concept of this invention that the same could, if desired, be formed into horizontally disposed coils in the upper portion of the chamber 20, or arranged in any suitable manner to spray fluid into the upper portion of the chamber 20. It is desired that a large number of orifices be provided in the spray section 42 so that fluids sprayed therefrom will be finely divided, and it is thought preferable that the sum of the cross sectional areas of the orifices substantially equal the inside cross sectional area of the spray section 42.

A vapor educting conduit 48 is provided for the chamber 20 and communicates with the upper portion thereof, it being understood that such conduit 48 will customarily be connected through pressure regulating means to fuel consuming devices, not shown.

While the tank 12 may be charged with liquefied gas by introducing the same into either of the chambers 18 and 20, as will be evident to those skilled in the art, in the preferred construction, the tank 12 is charged with liquefied gas through a filler conduit 50 communicating with the upper portion of the chamber 20. Obviously, the filler construction is provided with suitable shut-off valves or the like, indicated generally at 52, as is customary in this art.

The operation of the invention will be readily understood. Assuming the tank 12 to be charged with liquefied fuel so that the liquid is present in both chambers, it will be clear that the contents of the tank 12 will absorb heat from the surroundings of the tank to elevate the vapor pressure of the liquid fuel and to furnish the necessary latent heat of vaporization of the latter upon vaporization of the same. It will be ap-

parent that when vapor is drawn off through the conduit 48 from the chamber 20, the contents of the chamber 20 will be cooled by the attendant vaporization of its contents and that the pressure therein will be lowered below the pressure prevailing in chamber 18, whereupon liquid from the lower portion of chamber 18 will enter the conduit 30, as indicated by the arrow 54 in Figure 1, to be discharged as a fine spray in the upper portion of the chamber 20, as indicated by the arrows 56 in Figure 1. Such spraying of liquid into the upper portion of chamber 20 produces two desirable effects, that is, very great liquid-vapor interface surface areas are created that promote rapid vaporization to meet high fuel vapor demands, and the tendencies of liquid fuel mixtures to stratify inner chambers 18 and 20 is counteracted by unvaporized spray settling gently on the surface of the liquid in the chamber 20 inasmuch as such sprayed liquid comes from the bottom of the chamber 18. This latter effect will be appreciated when it is assumed that a mixture of propane and butane is used as a fuel. Inasmuch as these fuel constituents possess different physical properties, such as different vapor pressures, density, heating value, etc., it is apparent that to produce a substantially constant heating value fuel vapor, that the surface of the liquid mixture in the chamber 20 should be of substantially the same percentage composition throughout the depletion of the contents of the tank 12. This is, of course, realized to a marked extent in the use of the present invention by spraying the liquid from the bottom of the chamber 18 onto the top surface of the liquid in the chamber 20.

Substantially the reverse process takes place on charging the tank 12, inasmuch as the filling of the compartment 20 through the conduit 50, as indicated by the flow arrows 58 in Figure 2, will cause the liquid from the bottom of the chamber 20 to enter the conduit 34 and to be discharged into the top of the chamber 18 as indicated by the flow arrows 60 and 62, respectively, in Figure 2.

Generally, then, it will be seen that whenever a pressure differential of a predetermined extent exists in favor of either one of the chambers 18 and 20, liquid from the very bottom of that chamber will pass into the upper portion of the other chamber. Such action will, of course, normally occur whenever there is a temperature differential between the contents of the chambers, or whenever the percentage composition of the liquids in the compartments or chambers differ.

If it is desired that the chamber 20 be utilized entirely as a vaporization chamber, rather than as a fuel storage chamber, it is contemplated that a pressure reduction valve may be disposed in either of the conduit portions 28 or 30 upstream of the spray section 42, so that fluid will pass therethrough only when pressure in the chamber 18 exceeds that in the chamber 20 by a substantial predetermined amount, and the filler conduit 50 connected to the chamber 18 rather than the chamber 20 in which instance the conduit portions 32 and 34, and valve 40 could be dispensed with. Although this alternative construction is not shown, the value of the spring function of the apparatus to facilitate the formation of vapor in chamber 20 will be readily recognized. As a matter of fact, the vertical extension of the conduit portion 30 above the liquid level line in the chamber 18 serves in a sense as a pressure reduction valve in such conduit, inasmuch as the pressure in the chamber 18 must

exceed the pressure in the chamber 20 by a predetermined amount (the head of fluid in the conduit 30 above the liquid level in the chamber 18) before fluid from the chamber 18 is sprayed into the chamber 20.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. In liquefied fuel storage and vaporizing apparatus, a tank having a partition therein dividing the interior thereof into first and second chambers, a conduit having its inner end disposed within and adjacent the bottom of the first chamber, said conduit extending through the partition and including a spray section disposed within and adjacent the top of the second chamber, such spray section having a plurality of spaced spray orifices therein, and a check valve in the conduit preventing flow into the first chamber through the conduit.

2. In liquefied fuel storage and vaporizing apparatus, a tank having a partition therein dividing the interior thereof into first and second chambers, a conduit having its inner end disposed within and adjacent the bottom of the first chamber, said conduit extending through the partition and including a spray section disposed within and adjacent the top of the second chamber, such spray section having a plurality of spaced spray orifices therein, a check valve in the conduit preventing flow into the first chamber through the conduit, and vapor outlet means for the second chamber adjacent the top thereof.

3. In liquefied fuel storage and vaporizing apparatus, a tank having a partition therein dividing the interior thereof into first and second chambers, a conduit having its inner end disposed within and adjacent the bottom of the first chamber, said conduit extending through the partition and including a spray section disposed within and adjacent the top of the second chamber, such spray section having a plurality of spaced spray orifices therein, a check valve in the conduit preventing flow into the first chamber through the conduit, a further conduit having its inlet end within and disposed adjacent the bottom of the second chamber and having its outlet end disposed within the first chamber, a further check valve in said further conduit preventing flow into the second chamber through said further conduit, and vapor outlet means for the second chamber adjacent the top thereof.

4. In liquefied fuel storage and vaporizing apparatus, a tank having a partition therein dividing the interior thereof into first and second

chambers, a conduit having its inner end disposed within and adjacent the bottom of the first chamber, said conduit extending through the partition and including a spray section disposed within and adjacent the top of the second chamber, such spray section having a plurality of spaced spray orifices therein, a check valve in the conduit preventing flow into the first chamber through the conduit, a further conduit having its inlet end within and disposed adjacent the bottom of the second chamber and having its outlet end disposed within the first chamber, the outlet end of said further conduit being spaced above the inlet end of the first mentioned conduit, a further check valve in said further conduit preventing flow into the second chamber through said further conduit, and vapor outlet means for the second chamber adjacent the top thereof.

5. In a liquefied fuel storage and vaporizing apparatus having first and second chambers, a conduit having its inner end disposed within and adjacent the bottom of the first chamber, said conduit extending into the upper portion of said second chamber and including a spray section disposed within and adjacent the top of the second chamber for spraying liquid from the bottom of the first chamber into the top of the second chamber and a check valve in the conduit preventing flow into the first chamber through the conduit.

6. In a liquefied fuel storage and vaporizing apparatus having first and second chambers, a conduit having its inner end disposed within and adjacent the bottom of the first chamber, said conduit extending into the upper portion of said second chamber and including a spray section disposed within and adjacent the top of the second chamber for spraying liquid from the bottom of the first chamber into the top of the second chamber and a check valve in the conduit preventing flow into the first chamber through the conduit, a further conduit having its inlet end within and disposed adjacent the bottom of the second chamber and having its outlet end disposed within the first chamber, a further check valve in said further conduit preventing flow into the second chamber through said further conduit, and vapor outlet means for the second chamber adjacent the top thereof.
